DESIGN FOR A PORTABLE COMBINED SOUND AND PICTURE REPRODUCING APPARATUS

Vladimir J. Boor, Scotch Plains, N. J., and Arthur
J. Bradford, Grosse Pointe Farms, Mich.

Application December 14, 1939, Serial No. 88,896

Term of patent 14 years

To all whom it may concern:

Be it known that we, Vladimir J. Boor and Arthur J. Bradford, citizens of the United States, residing, respectively, at Scotch Plains, New Jersey, and Grosse Pointe Farms, Michigan, have invented a new, original, and ornamental Design for a Portable Combined Sound and Picture Reproducing Apparatus, of which the following is a specification, reference being had to the accompanying drawing, forming part thereof.

Figure 1 is a front perspective view of portable combined sound and picture reproducing appara-

tus showing my new design as it appears in a closed position, and

Figure 2 is also a front perspective view but with the device as it appears in the open or extended position.

The rear view of the apparatus is plain.

We claim:

The ornamental design for a portable combined sound and picture reproducing apparatus, substantially as shown and described.

VLADIMIR J. BOOR.
ARTHUR J. BRADFORD.
